(57) **CLAIM**

The ornamental design for a payment device, as shown and described.

DESCRIPTION

FIG. 1 is a front view of a payment device showing our new design.

FIG. 2 is a back view of the payment device of FIG. 1

FIG. 3 is a left view of the payment device of FIG. 1

FIG. 4 is a right view of the payment device of FIG. 1.

FIG. 5 is a top view of the payment device of FIG. 1.

FIG. 6 is a bottom view of the payment device of FIG. 1; and,

FIG. 7 is a front and right perspective view of the payment device of FIG. 1.

The broken lines shown in the drawings depict portions of the payment device that form no part of the claimed design.

1 Claim, 7 Drawing Sheets
